UNITED STATES PATENT OFFICE.

JOSEPH A. COSTELLO, OF CLEVELAND, OHIO, ASSIGNOR TO CLEVELAND CAR SPECIALTY COMPANY, OF CLEVELAND, OHIO, A CORPORATION OF WEST VIRGINIA.

CAR-ROOF FRAME.

1,181,573.

Specification of Letters Patent.

Patented May 2, 1916.

Application filed September 7, 1915. Serial No. 49,219.

To all whom it may concern:

Be it known that I, JOSEPH A. COSTELLO, a citizen of the United States of America, residing at Cleveland, in the county of Cuyahoga and State of Ohio, have invented certain new and useful Improvements in Car-Roof Frames; and I hereby declare the following to be a full, clear, and exact description of the invention, such as will enable others skilled in the art to which it pertains to make and use the same.

This invention relates to improvements in car-roof-frames, and pertains more especially to a car-roof-frame which comprises a carline comprising a trough which bridges the space between and extends across the tops of the laterally spaced side plates of said frame and having such contour over each side plate as to form opposite side walls of two air-conducting passageways which extend transversely of the top of said side plate and are arranged at opposite sides respectively and externally of said trough and in open relation at their outer ends with the atmosphere at the outer side of said side plate and communicate at their inner ends with the space at the inner side of said side plate.

One object of this invention is to have said carline not only capable of conducting any water received thereby to the outer sides of the side plates through the medium of the trough of said carline, and to have the end-portions of the carline so contoured that the carline upon its application to the side plates of the car-roof-frame is adequately seated on said side plates and any tendency of said carline to rock or tip laterally is effectually opposed, but to form within each end-portion of the carline two air-conducting passageways extending across the top of the adjacent side plate and arranged at opposite sides respectively and externally of the aforesaid trough and employed in conducting air from one to the other side of said side plate and thereby utilized in ventilating a car comprising said frame and in preventing sweating of the carline where the carline is exposed to the air within the car.

Another object is to produce an inexpensive ventilating carline which is strong and stiff in its end-portions.

Another object is to effect the reduction

to a minimum of the cost of constructing a car-roof-frame comprising my improved ventilating carline.

With these objects in view, and to the end of attaining any other advantage hereinafter appearing, this invention consists in certain peculiarities of construction, and combinations and arrangement of parts, hereinafter described, pointed out in the claims, and illustrated in the accompanying drawings.

In said drawings, Figure 1 is a top plan of a portion of a box-car embodying my invention. Fig. 2 is a vertical section on line 2—2, Fig. 1. Fig. 3 is a vertical section on line 3—3, Fig. 1. Fig. 4 is a vertical section on line 4—4, Fig. 3, looking inwardly. Fig. 5 is a section on line 5—5, Fig. 3, looking downwardly. Fig. 6 is a vertical section on line 6—6, Fig. 5. Figs. 3, 4, 5 and 6 are drawn on a larger scale than Figs. 1 and 2.

Referring to Figs. 1 and 2 of said drawings, A and A indicate the two laterally spaced horizontally arranged parallel side plates of a car-roof-frame. The side plates illustrated consist of metal bars, and each side plate is provided at the top thereof with a laterally and inwardly projecting substantially horizontally arranged flange a which extends longitudinally of said side plate, and said side plate is shown provided at the bottom with a laterally and outwardly projecting flange b. Figs. 1 and 2 show the space between the side plates A bridged by my improved carline which comprises a trough B which extends over and across the tops of the sides plates.

The trough B is provided at the top and externally with two laterally and outwardly projecting flanges b which extend longitudinally and from end to end of the trough and consequently over and across the tops of the side plates and are wider along the end-portions than along the central portion of the carline.

Preferably the trough B is uniform in width internally from end to end and arranged wholly above the side plates A and wholly between the outer sides of the side plates and terminates substantially at the junction of the top and outer side of each side plate.

Over each side plate A each flange b (see Figs. 3, 4, 5 and 6) has a depressed part b'

extending across the top of said side plate and along the longitudinal edge of the flange and terminating at the junction of the top and outer side of said side plate. Each 5 de-pressed part b' of each flange b is riveted, as at 8, to the top flange a of the adjacent side plate and spaced from the adjacent side of the trough so as to effect the formation, between said side of the trough and 10 said depressed part of said flange, of an air-conducting passageway C arranged externally of the trough wholly between said side of the trough and the longitudinal edge of said flange and wholly above said side plate, 15 and preferably said passageway is parallel with the trough and straight from end to end and extends longitudinally of the trough and across the top of the adjacent side plate. It will be observed, therefore 20 that the carline illustrated has such contour along each end-portion thereof as to form two parallel air-conducting passageways which extend longitudinally of the trough and are arranged at opposite sides respectively of said end-portion and externally of 25 the trough, that opposite side walls of said passageways are formed by said end-portion of the carline, and that said passageways are in open relation at their outer ends 30 with the atmosphere at the outer side of said side plate and consequently in communication with the atmosphere externally of a car provided with a roof embodying my invention and communicate at their inner ends 35 with the space at the inner side of said side plate and consequently with the room internally of said car.

Across the top of the trough B , at points between the side plates A , extend the ridge-40 pole D and purlins E , and said members D and E rest on the flanges b and are secured to said flanges in any approved manner, and on said members D and E rest the roofing-boards G having an outer metal covering g . 45 The carline-trough B extends into the lower portions of wooden bars H which rest on and extend longitudinally of and are secured to the top flanges a of the side plates A , and said bars are recessed, as at 10, to 50 accommodate the location of said trough which terminates therefore within the recesses 10 in said bars, and the roofing-boards also rest on and are secured to said bars. The bars H extend widthwise outwardly 55 beyond the ends of the carline and beyond the outer sides of the side plates A and are provided at their outer side with fascia h shown covered at its outer side by the metal covering g of the roof. The fascia h of each 60 bar H extends along the outer side of the adjacent side plate A and is spaced, as at K , from said side plate and from the trough B , and the space K thus formed between the inner side of said fascia and the outer 65 side of the said side plate and between said

fascia and the trough is open at the bottom and communicates at the top with the adjacent air-conducting passageways C .

Obviously a car having a roof embodying my invention is adequately ventilated 70 through the medium of my improved carline hereinbefore described. Sweating of said carline where the carline is exposed to the air within the car is prevented. Said carline is preferably made from an oblong 75 rolled steel plate pressed into the shape required to form the carline and has its end-portions meritoriously serving as ventilators next externally of the trough of the carline, and I would here remark that the uniformity in the internal width of the trough of a carline thus made results in the formation of flanges b which are wide enough along the end-portions of the trough to permit of the formation of passageways C which, 80 as shown, are as wide at their outer ends as at any point between their ends and have an adequate air-conducting capacity.

What I claim is:—

1. In a car-roof-frame, the two laterally spaced side plates, and a metal carline comprising a trough which bridges the space between and extends over the side plates and is provided at the top and externally with two laterally and outwardly projecting flanges arranged at opposite sides respectively and extending from end to end of the trough, there being formed, over each side plate, two passageways extending longitudinally of the trough at opposite sides 100 respectively of the adjacent end-portion and externally of the trough, which passageways are in open relation at their outer ends with the atmosphere at the outer side of the adjacent side plate and communicate at their inner ends with the space at the inner side of said side plate, each passageway being adapted to conduct air from one to the other side of the adjacent side plate and arranged wholly between the adjacent side of the 110 trough and the longitudinal edge of the adjacent flange of the trough.

2. In a car-roof-frame, the two laterally spaced side plates, and a metal carline comprising a trough which bridges the space 115 between and extends over the side plates and is provided at the top and externally with two laterally and outwardly projecting flanges arranged at opposite sides respectively and extending from end to end of the trough, there being formed, over each side plate, two air-conducting passageways extending longitudinally of the trough at opposite sides respectively of the adjacent end-portion and externally of the trough, 120 which passageways are in open relation at their outer ends with the atmosphere at the outer side of the adjacent side plate and communicate at their inner ends with the space at the inner side of said side plate, 125

each passageway being arranged wholly between the adjacent side of the trough and the longitudinal edge of the adjacent flange of the trough and wholly above the adjacent side plate.

3. In a car-roof-frame, the two laterally spaced side plates, and a carline comprising a trough which bridges the space between and extends over the side plates, said carline having such contour along each end-portion thereof as to form two air-conducting passageways which extend longitudinally and are arranged at opposite sides respectively of said end-portion and externally of the trough and in open relation at their outer ends with the atmosphere at the outer side of the adjacent side plate and communicate at their inner ends with the space at the inner side of said side plate.

4. In a car-roof-frame, the two laterally spaced side plates, and a metal carline comprising a trough which bridges the space between and extends over the side plates and is provided at the top and externally with two laterally and outwardly projecting flanges which extend longitudinally of the trough and over the side plates, each end-portion of each flange having a depressed part which is arranged over the adjacent side plate and extends longitudinally of said flange and transversely of said side plate, there being an air-conducting passageway formed between said depressed part of said flange and the adjacent side of the trough, which passageway extends longitudinally of the trough and is in open relation at its outer end with the atmosphere at the outer side of said side plate and communicates at its inner end with the space at the inner side of said plate.

5. In a car-roof-frame, the two laterally spaced side plates, and a metal carline comprising a trough which bridges the space between and extends across the tops of the side plates and is uniform in width internally from end to end and provided at the top and externally with two laterally and outwardly projecting flanges which extend from end to end of the trough and are wider along their end-portions than along their central portion, each end-portion of each flange having a depressed part which is arranged over the adjacent side plate and extends longitudinally of said flange and rests on said side plate, there being a passageway formed between said depressed part of said flange and the adjacent side of the trough, which passageway is parallel with the trough and adapted to conduct air across the top of said side plate from one to the other side of said side plate, said passageway being as wide at its outer end as at any point between its ends.

6. In a car-roof-frame, the two laterally spaced side plates, and a carline comprising

a trough which bridges the space between and extends over the side plates, said car-line resting at each side of the trough on each side plate at a point spaced from said side of the trough, there being an air-conducting passageway formed between said point and the adjacent side of the trough, which passageway is in open relation at its outer end with the atmosphere at the outer side of the adjacent side plate and is arranged externally of the trough and wholly above and transversely of said side plate. 70 75

7. In a car-roof-frame, the two laterally spaced side plates, roofing-supporting bars mounted on and extending longitudinally of the side plates, and a carline comprising a trough which bridges the space between and extends over the side plates and also extends into the lower portions of said bars, said bars extending widthwise outwardly beyond the ends of the carline and being provided at their outer sides with fascia which extends along the outer side of the adjacent side plate and is spaced from said side plate and from the trough, there being formed over each side plate two air-conducting passageways arranged at opposite sides respectively of the adjacent end-portion and externally of the trough, which passageways are in open relation at their outer ends with the space between said end-portion of the trough and the adjacent fascia and communicate at their inner ends with the space at the inner side of the adjacent side plate.

8. In a car-roof-frame, two laterally spaced side plates, roofing-supporting bars mounted on and extending longitudinally of the side plates, and a metal carline comprising a trough which extends between and into the lower portions of said bars and is provided at the top and externally with two laterally and outwardly projecting flanges arranged at opposite sides respectively and extending from end to end of the trough, said bars extending widthwise outwardly beyond the ends of the carline and being provided at their outer sides with fascia which extends along the outer side of and is spaced from the adjacent side plate, there being formed along each end-portion of the trough two air-conducting passageways arranged at opposite sides respectively of said end-portion and externally of the trough, which passageways are in communication at their outer ends with the space between the adjacent side plate and the adjacent fascia and communicate at their inner ends with the space at the inner side of said side plate, each passageway extending across the top of the adjacent side plate and being arranged wholly between the adjacent side of the trough and the longitudinal edge of the adjacent flange of the trough. 125

9. In a car-roof-frame, a carline compris- 130

ing a trough which is adapted to bridge the space between and extend over the side plates of said frame and having each end-portion thereof contoured to form opposite 5 side walls of two air-conducting passageways which are arranged at opposite sides respectively and externally of the trough and extend inwardly longitudinally of the trough from the outer extremity of said 10 end-portion of the carline.

10. In a car-roof-frame, a carline comprising a trough adapted to bridge the space between and extend over the side plates of said frame and provided at 15 the top and externally with two laterally and outwardly projecting flanges which extend longitudinally and from end to end of the trough, each end-portion of each flange being contoured to form the 20 outer side wall of an air-conducting passageway which is arranged externally of the trough and extends inwardly from the outer extremity of said end-portion of said flange.

11. In a car-roof-frame, a carline comprising a trough adapted to bridge the space 25

between and extend over the side plates of said frame and uniform in width internally from end to end and provided at the top and externally with two laterally and outwardly projecting flanges which extend 30 longitudinally and from end to end of the trough and are wider along their end-portions than along their central portion, each end-portion of each flange having a part thereof depressed and having said depressed 35 part extending longitudinally of said flange, there being an air-conducting passageway formed between said depressed part of said flange and the adjacent side of the trough, which passageway is arranged externally 40 and longitudinally of the trough, said passageway being as wide at its outer end as at any point between its ends.

In testimony whereof, I sign the foregoing specification, in the presence of two witnesses. 45

JOSEPH A. COSTELLO.
